UNITED STATES PATENT OFFICE.

MILLARD F. HAMSLY, OF BROOKLYN, NEW YORK.

FIREPROOF WINDOW.

No. 874,501.

Specification of Letters Patent.

Patented Dec. 24, 1907.

Application filed August 13, 1907. Serial No. 388,369.

To all whom it may concern:

Be it known that I, MILLARD F. HAMSLY, of Brooklyn, in the county of Kings and State of New York, have invented a certain new and useful Improvement in Fireproof Windows; and I do hereby declare the following to be a full, clear, and exact description of the same, reference being had to the accompanying drawings, forming a part of this specification, and to the figures and letters of reference marked thereon.

This invention relates to improvements in metal fireproof windows of that type wherein the several parts are usually formed of sheet metal, the objects of the invention being to provide a window the parts of which may be shaped up in dies and when assembled will resist to the maximum any tendency to separate or warp under the influence of heat or sudden and extreme changes in temperature and which will also offer the maximum resistance to binding or indentation at salient points.

Further objects of the invention are to provide a window having tight or weatherproof joints both between the relatively fixed parts and between the relatively movable members constituting the whole structure.

Referring to the accompanying drawings: Figure 1 is a vertical section, partly broken away through a window embodying the present improvements. Fig. 2 is a horizontal section, on line 2—2, but on a somewhat larger scale and with intermediate parts broken away, the plane of the section being through the upper half of the sash. Fig. 3 is a similar section, line 3—3, through one half of the window. Fig. 4 is a detail sectional perspective of a part of the casing and upper part of a sash. Fig. 5 is a detail vertical section through the sill and sash in proximity to the muntin in one sash, part of the latter also being in section. Fig. 6 is a perspective view of one corner of a sash, the parts being separated and broken away to show the manner of assembling. Fig. 7 is a vertical section through the sill and base of a mullion or munnion. Fig. 8 is a detail horizontal section showing the preferred means for supporting the transom bar. Fig. 9 is a detail of the bottom rail of the sash.

Like letters of reference in the several figures indicate the same parts.

As shown in the drawings, the frame for

the window is made up of a sill A, jambs B, head or lintel C, center post or mullion D and transom bar E, but it will be understood that any number of posts or mullions may be employed, or none at all, depending upon the width of the window, so too, while upper and lower sash openings are formed by the transom bar, the said bar may be omitted, particularly if the window is short vertically, and only a single sash is desired.

The sill A is formed up of sheet metal by substantially straight longitudinal folds and bends, thus on the inner side of the window the sheet metal is folded closely around an angle iron core bar A', so as to embrace the outer face and both edges of the iron. Where the sheet metal folds in under the upper or outer edge of the angle iron it forms a recess a into which the edge of the sash passes to form a tight joint as will be presently explained. From the recess a the metal forming the sill is inclined to form two inclined water tables a' a'', between which is an outwardly inclined riser a''' and at the outer edge the metal extends downwardly in the form of a skirt a'', the table a'' and skirt a''' overlying an angle bar A'', the flanges of which preferably form an obtuse angle as shown clearly in Figs. 1, 5 and 8. The edges of the sheet metal forming the sill are clamped tightly around the angle irons A' and A'' respectively, thus the salient edges of the sill are strengthened sufficiently when backed by the cement setting to withstand any stress short of such as would completely destroy the window.

The three exposed faces of the jambs B are preferably formed of two pieces of sheet metal united on the inside of the casing by a folded seam at b into which seam one edge of a weather strip or channel piece F may be folded throughout the lower half of the sash, as shown in Fig. 3. The inner and outer faces of the jambs are made with relatively deep vertical channels G, G', respectively, while the intermediate face G'' is substantially flat and at right angles to the plane of the sash. The formation of the channels G and G' in the faces of the jamb gives an internal configuration which is adapted to receive and retain a rectangular core bar H one face of which fits smoothly against the inside of the intermediate face G'' of the jamb and the edges of which fit into and support the edge ribs or projections forming the outer sides of

the said channels, thus the sheet metal of the jambs is firmly backed at salient edges to resist deformation through any cause.

The head or lintel C, Fig. 1, has its outer, 5 inner and intermediate sides formed of a single piece of metal, the intermediate face being formed with a channel c for the reception of the edge of the sash, said channel opening inward so as to be entered by the 10 outer edge of the top rail of the sash as it moves outwardly to closed position. At the inner side of the channel c the face inclines in a plane substantially parallel with the water tables of the sill and transom bar whereby a 15 sash pivoted on a horizontal axis will close tightly at top and bottom all as shown clearly in Fig. 1.

Where a wide window or one requiring more than one sash side by side is desired, 20 the casing is made of sufficient width to admit one or more mullions or vertical intermediate parts each intermediate face of which will conform to that of the jambs. Each mullion is made up preferably of two 25 pieces seamed together at d, d, such seams corresponding to the seams b in the jambs. The mullions also have channels D' D² corresponding to the channels G G' in the jambs with internal core bars D³ forming the backing 30 for the salient edges. At top and bottom where the mullions join the sill and lintel the outer and inner faces are preferably extended and doubled back around the edges of the lintel and sill, as shown clearly in Fig. 35 7, whereby the mullions will be held firmly in position, but it will be understood that additional fastening means of usual or preferred character may also be employed when desired.

40 In fireproof windows of the character to which the present invention relates it is desirable to make use of sash pivoted on horizontal axes so as to tend to close automatically if released, and it is also desirable that 45 the sash should be of restricted height and hence it is usual to divide the casing into vertical sections by transom bars. As shown in the accompanying drawings, particularly in Fig. 1, a transom bar E is employed. This transom bar is preferably made up of two pieces of sheet metal seamed together at e e', the seams forming the outer 50 walls of recesses into which the edges of the top and bottom sash fit when closed. The 55 top and bottom faces of the transom bar conform essentially to the form of the central parts of the sill and lintel so as to fit the edge faces of the sash accurately and with an outward inclination to prevent the entry of 60 water. A flat or rectangular core piece E' forms a filler for the transom and gives the same great rigidity and strength in addition to affording a ready means whereby the ends of the bar may be firmly fastened to the 65 jambs and mullions. The preferred connec-

tion is shown in detail in Fig. 8, where it will be seen that dowels or tenons E² connect the ends of the rigid core E' with the cores H or D³ as the case may be.

In setting the casing it is usual to form the 70 window opening of substantially the shape shown by the lines I I' in Figs. 1 and 2, and to bed the casing in cement which may be poured or otherwise placed in the cavities between the wall and casing, as shown at i i'. 75 In most instances it is desirable to leave the jambs and lintel hollow and for this purpose recessed fillers K are seamed to the edges of the jambs and lintels, the recesses in said plates, as shown in Fig. 2, serving to receive 80 cement to form keys of greater size for retaining the casing firmly against displacement.

The sash, which is of special design for 85 cooperation with the casing described, but which embodies features common to both casing and sash, is formed with sheet metal top, bottom and side rails, wrapped or folded about core pieces for uniting the parts and giving additional rigidity. 90

The core pieces M of the sash are of substantially rectangular section, one being provided for each rail and with one end M' bent up at right angles to enter the adjoining rail as is well illustrated in Fig. 6. The sheet metal N is bent closely around the core pieces, the edges at N' on one side of the core piece being bent out at an angle to form the channel for the glass between them. Between the parts N' forming the side walls of 100 the glass channel a U-shaped channel iron O is located and held in place by the inturned extremé edges N² of the sheet metal covering, thus not only are the edges of the covering prevented from spreading, but the walls of 105 the glass channel are made very rigid.

The bottom rail of the sash should have an apron to overlie the riser a³ of the sill and for this purpose the sheet metal cover of the bottom rail is extended at one edge of the core 110 and bent downwardly as shown at P, in Fig. 9. In this figure and Figs. 1 and 5, it will also be seen that this bottom rail is inclined to the plane of the sash and consequently the walls of the glass channel are inclined to the plane of the core, one side of the channel being made somewhat longer than the other to bring the edges up to the same level. At the end where the core is bent up at right angles one edge is cut away as at P' to permit said 115 end to enter the side rail correctly.

The preferred construction of side rail for the sash is shown in Fig. 4, wherein it will be seen that the sheet metal cover is in two parts seamed or with their edges folded together at 125 Q, and having a separate strip R with its edge folded in the seam, the free edge of the strip being formed into a channel R', the outer wall of which enters the channel G in the casing. Obviously the strip R, R', only 130

extends from the pivotal center to the top or bottom of the sash, thus, as shown, it extends to the top of the sash and is located on the inner side. The joint between the other half 5 of the sash and casing is bridged by the strip F before referred to and shown particularly in Fig. 3.

To insert the glass S, its upper edge is passed up into the channel at the top of the 10 sash, which channel is usually made somewhat deeper than at the sides and bottom, the lower edge is dropped into the bottom channel and the glass moved edgewise into the channel of the side rail. Two or more 15 panes of glass are employed of such width as to permit the entry of both and in order to fill the space between the panes of glass a "muntin", the parts of which are clamped to the glass is employed. The muntin shown 20 (Figs. 2, 3 and 5) is composed of two parts, the part on the outside embodying a sheet metal strip or bar having side flanges T with the edges turned back to rest against the glass and a central channel T' in which a solid 25 core bar T² is permanently mounted and held by rivets or similar fastenings.

The part of the muntin on the inside of the window is of somewhat similar formation save that the flanges t' are bent closely 30 around a wide flat core t² and the edges t³ of the strip are turned at right angles to the core so as to pass in between the adjacent 35 edges of the glass. Screws U passing through the inner half of the muntin and screwing 40 into the core bar T² serve to clamp the two parts firmly together. At the bottom of the sash the central part of the outer half of the muntin preferably extends down over the 45 walls of the glass channel as shown at U' in Fig. 5, while the inner half is cut away at a somewhat higher point to avoid contact with the sill and the outer face of the channel is bent in as at U² in said Fig. 5 to give a finished appearance.

The sash are mounted so as to swing inwardly at the top and outwardly at the bottom and for this purpose hinges are provided 50 of such form that they may be readily secured to the sash and casing or mullion. The upper leaves V of the hinges are preferably adjustably secured to the side rails of the sash by bolts v passing through slots in the hinges while the upper and lower leaves 55 of the hinges are secured together by pintle bolts V' said bolts being adapted to pass way through the mullion or casing and to be held in place by cotter pins or similar fastenings at the ends. Said lower leaves of the hinges are adapted to fit in the channels G (see Figs. 60 2 and 3) and in addition may be secured by rivets or bolts as usual. One hinge of each pair is provided with an extension W on each leaf to one of which a rod W' is loosely secured, and adapted to be adjustably clamped 65 to the other by a thumb nut and screw W²,

whereby the position of the sash may be controlled.

The pivotal axis of the sash is so located that if entirely free, the windows will automatically close in order to automatically 70 free the sash should fire occur in the vicinity of the window, a washer X, fusible at low temperature, is interposed between the thumb nut and rod W'. If the washer melts the rod is instantly freed from the clamp and 75 the window closes. In both the mullion and jambs small openings such as indicated at y, in Fig. 1, are preferably formed at top and bottom to afford ventilation and drainage.

When closed as shown in Fig. 2 it will be 80 noted that the outer edges of the sash are substantially flush with the edges of the walls of the channels and as a result storm water will be blown into the channels, rather than between the sash and casing, the channels forming, in effect, ducts for protecting the parting opening and conducting all storm water down away from the sash.

Having thus described my invention, what I claim as new and desire to secure by Letters Patent, is:

1. A fireproof window embodying a casing formed of sheet metal and internal longitudinal core pieces of flat bar metal along the salient edges held in place by the folds and 95 bends of the sheet metal passing around both edges of the bar.

2. A fireproof window embodying a casing formed of sheet metal having channels in its outer and inner faces and an internal core of 100 bar metal held by the walls of said channels to form a backing for the intermediate face of the casing.

3. A fireproof window, embodying a casing, formed of sheet metal and including a 105 sheet metal sill having an internal angle bar core about both the edges of which the sheet metal is folded to retain the core in position.

4. In a fireproof window a sheet metal sill embodying an internal core of bar angle iron 110 forming a backing for two of the faces of the sill.

5. In a fireproof window, a sheet metal sill embodying an internal core of bar angle iron forming a backing for two of the faces of the 115 sill, folds of said sheet metal embracing the core to retain the same in position.

6. In a fireproof window, a sheet metal sill embodying bar angle iron cores in the inner and outer salient edges, the sheet metal being 120 folded to retain said cores in position.

7. In a fireproof window a sheet metal sill embodying a bar angle iron core in the inner salient edge, the sheet metal being folded around the outer edge of the core to form a 125 channel beneath the edge of said core and to retain the core in position to support the fold of the sheet metal.

8. In a sheet metal fire proof window a sheet metal mullion having oppositely dis- 130

posed channels in its inner and outer faces and internal bar metal cores held in place by the walls of said channels to support the intermediate faces of said mullion.

5 9. In a sheet metal fireproof window, a sheet metal mullion having channels in its inner face and a sash pintle bolt bridging the channels and passing through the portion of the mullion between the channels.

10 10. In a fireproof window, the combination with the metal casing of a metal sash frame embodying a flat solid metal core and a sheet metal envelop extending around and having its edges bent to project at an angle 15 from one of the flat faces of the core to form a channel for the panes of glass.

11. In a fireproof window, the combination with the metal casing, of the metal sash frame embodying a metal core and U-shaped 20 channel iron and a sheet metal envelop for said core having its edges bent outwardly from the core and embracing the flanges of the channel iron to form the glass channel.

12. In a fireproof window, the combination with the metal casing embodying bar 25 metal cores and sheet metal envelops in which said cores are held, of a transom bar

embodying a bar metal core connected at the ends with the cores in the casing and a sheet metal envelop for said core having channels 30 for the sash; substantially as described.

13. In a fireproof window, the combination with the metal casing and metal sash pivotally mounted therein to close automatically, of a connector for holding said 35 sash open embodying a rod and a screw clamp therefor having a fusible metal washer interposed in the clamping parts whereby the rod and sash will be released when the washer melts.

14. In a fireproof window, the combination with the metal casing and metal sash, of a hinge connecting the sash and casing, projections on the leaves of the hinge, a rod loosely connected with one of said projections, and a clamp for said rod on the other projection embodying a fusible metal washer 45 in the clamping parts whereby the rod and sash will be released when the washer melts.

MILLARD F. HAMSLEY.
